UNITED STATES PATENT OFFICE.

WILLIAM McGIVEN, ALVIN L. NICHOLS, AND GEORGE DARNELL, OF GROVE CITY, OHIO.

CHEESE-KNIFE.

SPECIFICATION forming part of Letters Patent No. 349,732, dated September 28, 1886.

Application filed February 9, 1886. Serial No. 191,380. (No model.)

To all whom it may concern:

Be it known that we, WILLIAM McGIVEN, ALVIN L. NICHOLS, and GEORGE DARNELL, citizens of the United States, residing at 5 Grove City, in the county of Franklin and State of Ohio, have invented a certain new and useful Improvement in Cheese-Knives, of which the following is a specification.

Our invention relates to improvements in 10 knives for cutting cheese, and is particularly adapted for the use of the retail dealers therein; and the objects of our invention are, first, to produce a simple, cheap, and effective cheese-cutting device, so constructed as to 15 admit of an even vertical cut being made from the center to the edge of the cheese at any desired point therein; second, to lessen the difficulty usually incurred in cutting the cover of a cheese. We accomplish these 20 objects in the manner illustrated in the accompanying drawings, in which—

Figure 1 represents, partly in section, a cheese being cut by our device. Fig. 2 is a front elevation of our improved device with the knife closed. Fig. 3 is a plan view, and Fig. 4 is a rear view of the upper end of the knife-sheath.

Similar letters refer to similar parts throughout the several views.

30 A represents the sheath of the knife, which consists of a cylindrical metal post having a central vertical slot, *a*, open at its upper end and extending within a short distance of the bottom of the sheath, the latter being preferably pointed to admit of its being inserted 35 into a corresponding cut, *g*, in the center of the bottom of the cheese-box *g*, after having been pushed through the center of the cheese. B. A short transverse metal strip, *a'*, may 40 connect the two halves of the sheath formed by the slot near their top portion, and thus prevent the halves spreading or being squeezed together.

Within the slot *a*, near its lower end, is 45 loosely pivoted the end of a knife-blade, *c*, by means of a rivet or pin, *c'*, which, having rigid bearings in the sides of the sheath, passes through a short longitudinal slot, *d*,

cut in the knife-blade *c*, near its lower end. The knife-blade is provided with a suitable 50 handle, *h*, which is preferably so formed as to admit the fingers of the hand between the handle and the board or table *e*, on which the cheese-box rests.

The knife-blade *c*, when folded, rests in a 55 vertical position within the slot *a* of the sheath, and when in this position is adapted to be pushed through the center of the cheese, in which position it may be held firmly by grasping with the left hand a short handle, *f*, 60 which is made to project from one side, and near the top of the sheath, at right angles therewith, while the remaining hand may, by grasping the handle *h*, be employed to press down the knife-blade through the cheese, 65 which may be revolved until the place desired to be cut is reached.

In case difficulty is experienced in severing the covering of the cheese, the knife may be drawn inward and outward with a sawing motion until the tough portion is cut. This sawing motion is made possible by having the slot *d*, through which the pin passes, in the knife-blade.

In case it is found that the knife tends to 75 waver or bend in its downward course, we provide a metal guide-rod, *b*, which has its middle portion, which is slightly cut away on its front side, fitted into a notch cut in the upper end of the sheath. This rod extends 80 transversely above the cheese-box until slightly beyond the sides of same. Its ends are then bent downward at right angles, and its extremities secured by a screw or otherwise to the table or board *e*. The side of the knife 85 may be pressed against this guide-rod during its downward course, and thus prevent its wavering or bending.

We are aware that prior to our invention a knife has been used, pivoted within a slotted 90 sheath, and that knife-blades have been provided with slotted ends for pivoting the same. We do not therefore claim these points, broadly.

Having now fully described our invention, what we claim, and desire to secure by Letters Patent, is—

1. A cheese-cutting device consisting of a sheath, *A*, having a handle, *f*, and central vertical slot, *a*, within which is loosely pivoted the slotted end of a knife-blade, *c*, having a handle, *h*, substantially as and for the purpose specified.

2. In a cheese-cutting device, the combination of the sheath *A*, having a handle, *f*, and a central vertical slot, *a*, within which is pivoted the slotted end of a knife-blade, *c*, hav-

ing a handle, *h*, with the guide-rod *b*, fitted within the upper end of the sheath, substantially as and for the purpose specified.
